(54) **BEDSTEADS**

(76) Inventor: **Robert Miller**

Robert Miller of Glasgow, State of Kentucky,

Letters Patent,

The schedule referred to in these Letters Patent and making part of the same, containing a description in the words of the said Robert Miller himself of his improvement in Bedstead.

To all to whom these presents shall come,

Be it known that I Robert Miller of Glasgow in the County of Barren and State of Kentucky have invented a new and useful improvement in bedstead and that the following is a full & exact description of the construction of a bedstead invented by me.

The frame of a bedstead is prepared in the usual manner but without mortise or tenon, At the distinct height of the bed rails say two feet, a right angle frame (capable of containing the other) is made one side and end of which are firmly fixed, the other slides up by wedge or screw, under the rails are pieces to support them at a proper height, & the projections of the posts are countersunk in the frame, Into it the bedstead is put in proper position and very firmly clamped up.

There are 8 pieces of cast iron, & 14 of wrought which in the aggregate are named Brestles the former consists of 4 right angled knees, each leg being 16 inches long & broad $8\frac{1}{2}$ or upwards in thickness with two small rag wheels & their flats are catched, the faces of the legs are called prizes in each of which are at least three $\frac{3}{4}$ hole that receive wood screws of 3 & inches long, The corner is a little obtuse after which it is $\frac{1}{2}$ thick in it are two similar holes receiving screws of 1 & 1/2 inches the first binds the prize to the rails & the last going into the posts diagonally unites the three pieces of each corner into one solid body, whence the knees are termed bedders. The four iron bars are about one inch diameter square, round or eight cornered, they are placed

inside and parallel to the bearers, at one & one & a half inches therefore
and pass thru the pieces half an inch at each end, those of the side
into the middle of the end pieces & they of the end one inch back
in the side pieces they carry the bed and are named sustainers
supporting or Beavers. a side and end beaver have square axles well
fitted to their holes in the pieces & remain fixed when in place; the
other two have round axles one end of which bearing a lag wheel, to
wind & tighten the canvas, its catch works on a screw nail that
passes thru the pieces the axle behind these wheels has such
form as tends to draw in the bars when winding, which presses
the wheels against the pieces & permanently seats the after
tires at that end also,

A piece of $\frac{3}{16}$ square iron say 18 inches long is formed into
an open wrench at one end & screw driver at the other it is
the only instrument necessary to put up or take down this bed
steadily, a piece of wood put into the wrench gives the power of an
auger handle to him that drives the screws. & the wrench is
fitted to the ends of the supporters, with it a child may tighten
the canvas in a moment, it should lie on two pins inside of
the front rail, on one side of each beaver bar, 8 small
pyramidal blocks, are raised with a cold chisel to an angle
of 20 degrees they rise to one sixteenth of an inch, stand
transversely & pointing from the draft in winding the sacking
bottom they are permanent, catch the end of the linen in
stantly & retain their hold. (small pins may be drilled in, or
each beaver may be in two parts, which clamp the ends between
them but the first is the best of all modes. — a d sacking
bottom is made in the form of a double crop. the arms extending
16 or 20 inches from the body (which is about 6 inches, not
narrower than the beaver) that they may roll three or four times
round the supporters before the linen begins to bear. & leave 3
inches at each side to wind up future stanchions
No joint in the bedstone can move hence the head & foot

boards are slipped into shallow grooves in the posts; cast iron or
brass grooves might be screwed on but they destroy the uniformity
& beauty of the piece. To put on a canvas bottom, spread
the linen on the floor strong side up with the arms extended
hook the two fixed bearers their side and end arms, roll up to
within three inches of the body, lift them together turn and put
them in place; hook the other arms to their moveable bearers then
in place & wind up with the wrench, to any desired tightness.

A bedstead is taken down by one person in two minutes
thus lift out the head and foot boards, let go the sag which
take out their bearers unscrewing three nails in each end rail.

The contrary order is observed in putting them up. Bedsteads
subject to frequent removal or to journeys have their end rails
built of two pieces, they are overlapped two feet in the middle
& united into one by by two screws; they are taken down with
equal celerity & without disturbing the corners or leaving much
weight upon their knees.

Second and best manner of placing the supporting bars
lest careless workmen should leave room for the ingeps or eyes
of a single reptile at the angles a mode of placing the bearers
without perforating the bed rails is invented, which by leaving
nothing to chance perfects the bedstead.

Posts are cast with the knees rising on thin pieces (say half
an inch thick a broad arm projects parallel to the piece a
quarter thick leaving the other quarter vacant between them
in which the wheels move. These castings are formed in such
manner that the sustainability are dropped into grooves at once
and firmly maintain their position; they now rest between the
joists only, with the model are a complete full sized set
of patterns for the castings of a bedstead, several kinds of these
cast are loosely attached to their joists for the advantage of which
which is easily will be satisfactory. It is submitted to the
large kids will afford no other manner of fastement or

Hollow & hollowed frames would not make the most lasting, clean
and durable bottom.

All the ends must be painted which renders them vulnerable
to water and they soon fall to pieces. Phoenix frame fire hence one
piece of each set should record the year of their birth that
every house in future ages may possess what is now undetermined
a true Chronological era, this frame is joined to its bedstead
and pillars without mortises, tenons, pins, nut, cord, lace, line,
or any hole, it is firm to solidity, durable as wood & iron
Nor is there a single invisible lodgment for one of those per-
fidious vermin that have so long annoyed the human family
It never needs scalding whence it is called the Clean
firm and everlasting Bedstead
